UNITED STATES PATENT OFFICE.

ALFRED E. C. HALL, OF PHILADELPHIA, PENNSYLVANIA, ASSIGNOR TO UNITED SHOE MACHINERY CORPORATION, OF PATERSON, NEW JERSEY, A CORPORATION OF NEW JERSEY.

METHOD OF MANUFACTURING BOOTS AND SHOES.

Application filed August 9, 1922. Serial No. 580,670.

This invention relates to the manufacture of boots and shoes, and is herein described in connection with the manufacture of a child's molded counter turned shoe having 5 an underwedge and a nailed seat.

In the manufacture of shoes of this type it is customary to prepare a bottom member consisting of a molded and channeled sole having attached to the heel end thereof an underwedge, the underwedge having in its 10 forward edge a notch or other recess located in register with one end of the channel and adapted to receive the channel guide of the sewing machine which is used to attach the 15 sole to the upper, the purpose of thus allowing the channel guide to run into the underwedge being to ensure that the end of the seam last formed shall extend close to the edge of the underwedge. In preparing the 20 bottom member, it has been customary to die out or round the soles and underwedges separately; and, because of this procedure, it has been difficult to obtain uniformly accurate alinement or register of the edges of 25 the sole and underwedge.

According to the present invention the sole blank and the underwedge blank are clamped in proper relation to each other and rounded simultaneously. When the 30 parts have been cut in this manner their edges are in exact register and no subsequent trimming after the parts have been fastened together is necessary.

In manufacturing the combined sole and underwedge it has been customary to cut in the forward straight edge of the underwedge at the same time that the wedge is died out the notch, which has been referred to above. The straight edge must thereafter 40 be skived or beveled; and this notch has tended to make the result of the skiving operation uneven adjacent to the locality of the notch.

According to the present invention the 45 notch or other suitable recess is formed after the underwedge has been skived and preferably after it has been attached to the sole. As described, a notch is made by a pinking cutter, the sole being utilized as a cutting bed.

Referring now to the accompanying drawings, Figure 1 is an elevation of a portion of a

sole rounding machine which may be used in carrying out one step of the method, 55

Fig. 2 is a perspective of a pattern to which the sole blank and underwedge blank may be clamped,

Fig. 3 is a perspective showing the sole 60 blank and underwedge blank in superposed relation and resting upon the pattern,

Fig. 4 is a perspective of a sole which has been rounded,

Fig. 5 is a perspective of an underwedge 65 after it has been rounded,

Fig. 6 is a perspective of the underwedge after it has been skived along its straight edge,

Fig. 7 is a perspective of the completed 70 bottom member, the sole having been channeled and molded, the underwedge having been cemented to it, and the notch having been cut, and

Fig. 8 is a perspective showing how the 75 channel guide of the sewing machine travels into the notch.

The rounding machine a portion of which is shown in Fig. 1 is or may be substantially the same as the machine shown and described in the patent to Mayo No. 882,009 80 (March 17, 1908) except that a special pattern is used. The machine will not be described further than to explain that the work is clamped to a pattern 9 and while so held is cut or rounded by a knife 11 which is 85 caused to travel around the edge of the pattern. Rounding machines have been in extensive use for many years, and any suitable machine may be employed.

Ordinarily, the pattern is of a uniform 90 thickness throughout; but in the present case, a pattern having a recess 13 is employed to receive the underwedge blank 15. This blank, which may be any piece of leather or other suitable material of sufficient 95 size and having one straight edge may be used. The underwedge blank is placed in the recess 13 of the pattern with its straight edge in contact with the shoulder 17; and the sole blank 19 is superposed upon the underwedge blank in the manner shown in Fig. 3. The blanks and the pattern are then clamped together in the rounding machine and rounded in the manner indicated in Fig. 1.

After the rounding operation the sole has 105

the appearance shown in Fig. 4. It is next channelled or channeled and shouldered and then molded, the molding consisting in forming a break or bend across the sole in the vicinity of the heel breast line so that when the beveled underwedge, later to be described, is put in place its upper surface will be flush with the upper surface of the sole. The underwedge, after the rounding operation, has the appearance shown in Fig. 5. It is next skived or beveled along its breast edge to produce the effect shown in Fig. 6.

The underwedge, as thus far described, is cemented to the heel end of the molded sole 15 in such manner that the beveled edge lies over the break in the sole, after which a notch 21 is cut in the beveled edge, preferably by a pinking cutter, using the sole as a cutting bed, the notch being located in register with one end of the channel in the sole. The complete bottoming member is shown in Fig. 7 in which the finished sole is indicated at 190, the channel at 23, the shoulder at 25 and the finished underwedge at 150.

25 The bottoming member shown in Fig. 7 is incorporated in a turned shoe by assembling it, together with an upper which is wrong side out, upon a last and sewing the upper to the sole in the manner indicated in Fig. 8. 30 The sewing machine used for this sort of work is provided with a guide 27 which travels in the channel 23 and is located in advance of the needle 29. If, therefore, no notch 21 or similarly located recess were 35 provided, the stitches would end at a point spaced from the forward edge of the underwedge. The notch, however, permits the channel guide to travel into the underwedge a sufficient distance to permit the last stitch 40 to be made close to the underwedge.

By rounding the sole and underwedge together the edges of them which are exposed in the finished shoe may be brought into accurate alignment; and by making the notch 45 after the underwedge has been beveled and attached to the sole not only is the skiving operation facilitated but the notch may be located in accurate register with the end of the channel.

50 Having thus described my invention, what I claim as new and desire to secure by Letters Patent of the United States is:—

1. The method of preparing an article 55 consisting of a sole and underwedge for incorporation in a shoe which comprises clamping a sole blank and an underwedge blank in superposed relation, rounding the blanks while so clamped before they are incorporated in the shoe and thereafter attaching the underwedge to the sole and completing the manufacture of the article.

2. The method of preparing an article 60 consisting of a sole and underwedge for incorporation in a shoe which comprises 65 rounding the underwedge blank and the sole

blank at a single operation, attaching the underwedge to the sole and thereafter cutting a recess in the edge of the underwedge located in position to receive the channel guide of the sewing machine used to attach 70 the sole to the upper of the shoe.

3. The method of preparing an article 75 consisting of a sole and underwedge for incorporation in a shoe which comprises rounding the underwedge blank and the sole blank at a single operation, attaching the underwedge to the sole and thereafter cutting a recess in the edge of the underwedge, using the sole as a cutting bed.

4. The method of preparing an article 80 consisting of a sole and underwedge for incorporation in a shoe which comprises clamping a sole blank and an underwedge blank in superposed relation, rounding the two blanks while so held, and thereafter 85 completing the manufacture of the article including cutting a recess in the edge of the underwedge.

5. The method of preparing an article 90 consisting of a sole and underwedge for incorporation in a turned shoe which comprises clamping a sole blank and an underwedge blank in superposed relation, rounding the two blanks while thus held, channeling and molding the sole, scarfing one edge of the 95 underwedge, attaching the scarfed underwedge to the heel end of the sole, and making in the scarfed edge of the underwedge a recess adapted to receive the channel guide of the sewing machine used to attach the 100 sole to the upper of the shoe.

6. The method of preparing an article 105 consisting of a sole and an underwedge for incorporation in a shoe which comprises holding a sole blank and an underwedge blank temporarily in proper superposed relation, rounding the blanks while so held before they are incorporated in the shoe and thereafter attaching the underwedge to the sole.

7. The method of preparing an article 110 consisting of a sole and an underwedge for incorporation in a turned shoe which comprises clamping a sole blank and an underwedge blank in superposed relation, rounding the two blanks while thus held, and thereafter separating the two blanks, channeling and molding the sole blank and scarfing the breast edge of the underwedge blank.

8. The method of preparing an underwedge 115 which comprises dieing out the underwedge, rounding the underwedge, beveling the breast edge thereof and thereafter cutting in the beveled breast edge a notch spaced from the sides of the underwedge and 120 so located that when the underwedge is in proper position upon a channeled sole, the notch will register with one end of the channel.

9. The method of preparing an article con- 130

sisting of a sole and an underwedge for incorporation in a shoe which comprises clamping a sole blank and an underwedge blank in the superposed relation which they are to occupy in the finished shoe, rounding the blanks simultaneously while so clamped before they are incorporated in the shoe, and thereafter attaching the underwedge to the sole and completing the manufacture of the article.

10. The method of preparing an article consisting of a sole and an underwedge for incorporation in a shoe which comprises clamping a sole blank and an underwedge blank in the superposed relation which they are to occupy in the finished shoe, progressively trimming the entire sole blank and the rear and sides of the underwedge blank

to the desired outline while so clamped before they are incorporated in the shoe, and thereafter attaching the underwedge to the sole and completing the manufacture of the article.

11. The method of preparing an article consisting of a sole and an underwedge for incorporation in a turned shoe which comprises clamping a sole blank and an underwedge blank in superposed relation, rounding the two blanks while thus held, channeling and molding the sole, scarfing one edge of the underwedge, and attaching the scarfed underwedge to the heel end of the sole.

In testimony whereof I have signed my name to this specification.

ALFRED E. C. HALL.
